[57] CLAIM

The ornamental design for a combined packaging container and lid, as shown.

DESCRIPTION

FIG. 1 is a top perspective view of a combined packaging container and lid showing my new design;

FIG. 2 is a bottom perspective view thereof;

FIG. 3 is a top perspective view thereof without the lid;

FIG. 4 is a bottom perspective view thereof without the lid;

FIG. 5 is a top perspective view of the lid thereof;

FIG. 6 is a bottom perspective view of the lid thereof;

FIG. 7 is a top perspective view of a modified form of the container of my new design;

FIG. 8 is a bottom perspective view thereof;

FIG. 9 is a top perspective view of a modified form of the lid of my new design, for use with the container of FIGS. 7 and 8;

FIG. 10 is a bottom perspective view thereof;

FIG. 11 is a side view in elevation of the container of FIG. 7;

FIG. 12 is an end view in elevation of the container of FIG. 7;

FIG. 13 is a side view in elevation of the container of FIG. 3;

FIG. 14 is an end view in elevation of the container of FIG. 3;

FIG. 15 is a side view in elevation of the lids of FIG. 5 and FIG. 9;

FIG. 16 is an end view of the lids of FIG. 5 and FIG. 9; and

FIG. 17 is a cross-sectional view taken along line 17—17 of FIG. 6.
